UNITED STATES PATENT OFFICE.

JOSEPH N. BURNO, OF CHICAGO, ILLINOIS, ASSIGNOR TO BUDDE & WESTERMANN, A CORPORATION OF NEW YORK.

LIQUID DISPENSER.

Application filed February 15, 1924. Serial No. 693,006.

To all whom it may concern:

Be it known that I, JOSEPH N. BURNO, a citizen of the United States, and a resident of Chicago, county of Cook, State of Illinois, have invented certain new and useful Improvements in Liquid Dispensers, of which the following is a specification.

This invention relates to liquid dispensers. An important object of the invention is

10 to provide in a device of the character mentioned an improved means whereby the flow of liquid from one source of supply may be established or discontinued irrespective of and independently of another source as desired.

15 Another object of the invention is to provide in a device of the character mentioned a means whereby the flow of liquid from the independent sources may be established simultaneously to effect an equal or substantially equal flow of liquids.

20 A further object of the invention is to simplify generally the construction of the several elements entering into the combination and provide a device of the character mentioned which is reliable in operation and capable of withstanding the severe usage incident to varying conditions under which the apparatus may be required to operate.

25 Other objects and certain advantages of the invention will become apparent from the following description when taken in connection with the accompanying drawings in which—

30 Figure 1 is a side elevation of the device embodying my invention.

Figure 2 is a front elevation of the device.

35 Figure 3 is a transverse sectional view taken on line 3—3 of Figure 1.

40 Figure 4 is a top plan view of the device with the liquid container receptacle removed.

45 Figure 5 is a bottom view of the device, the valve operating lever being shown in section.

Figure 6 is a sectional view taken on line 6—6 of Figure 4.

50 Figure 7 is a sectional view taken on line 7—7 of Figure 4.

In the drawings, wherein for the purpose of illustration is shown what I at present consider the preferred form of my invention, the numeral 5 indicates a body in the form of a casting having a stem 6 associated therewith which is bored to provide a passage 7, the stem being provided at its end

with a flange and internally screw-threaded pipe coupling 8 adapted to connect the device to a suitable source of liquid supply, not shown. The passage 7, as will be noted particularly from Figure 7, terminates in a chamber 9 communicating with an escape opening 10 through which a liquid such as coffee, for example, is adapted to escape under conditions hereinafter more particularly described. The casting 5 is also provided with a vertical passage 11 communicating with an escape opening 12 through which a liquid such as milk is adapted to escape under conditions hereinafter more particularly pointed out. The upper end of the passage 11 is screw-threaded as shown at 13 and is adapted for the reception of the screw-threaded end of a depending nipple 14 connected to and communicating with a liquid container receptacle 15 into which is adapted to be placed a liquid container such as a bottle 16 adapted for the reception of a liquid such for example as milk. It will be appreciated that while I have shown the source of milk supply in the form of a bottle 16 this bottle may be dispensed with as well as the liquid container receptacle 15, in which case the passage 11 may be connected directly as by means of a pipe, not shown, to a suitable reservoir, also not shown, but adapted for the reception of milk.

55 The flow of liquid from the passages 7 and 11 is controlled through the instrumentality of valves 17 and 18, respectively. These valves respectively comprise wings 19 and 20, carrying extensions 21 and 22 having openings 23 and 24 formed therein, which openings are provided with vents 25 and 26 adapted, upon movement of the wings 19 and 20, to establish communication between the passages 7 and 11 and the openings 23 and 24, respectively. The wings 19 and 20 are pivotally connected to or loosely mounted upon shafts 27 and 28, respectively, which are journaled to the casting 5 and adapted to rotate with respect thereto. To these shafts are rigidly connected valve operating arms 29 and 30, confined between lugs 31 and the extensions 21 and 22, carried by the wings 19 and 20 so that when the arms 29 and 30 are moved through the instrumentality of the shafts 27 and 28 the wings 19 and 20 are correspondingly actuated. While the wings 19 and 20 are so

locked to the shafts 27 and 28 as to rotate therewith they are nevertheless free to slightly move longitudinally thereupon in order to permit an intimate engagement of the wings 19 and 20 with the faces of the casting 5 within which the exit openings 10 and 12 are formed. This intimate engagement of the wings 19 and 20 with the face of the casting 5 is effected through the instrumentality of flat thrust springs 32 and 33 disposed intermediate the arms 29 and 30 and the wings 19 and 20, respectively. The thrust springs 30 and 31 are slightly bowed, as shown most clearly in Figure 1, and are retained in position upon the wings 19 and 20 by reason of the fact that their outer ends are confined within notches 34 and 35 formed in the wings 19 and 20, whereas their opposite ends are maintained in engagement with lugs 36 and 37 carried at the free ends of the wings 19 and 20 respectively.

To the shafts 27 and 28 are connected hub members 38 and 39 with which are integral-
ly formed lugs or arms 40 and 41 carrying pins 42 and 43 against which rest corresponding ends of torsional springs 44 and 45 coiled around the shafts 27 and 28, and held thereon by means of collars 38' and 39'.
These springs terminate in relatively long arms adapted to engage the stem 6 on the under side thereof and when assembled are maintained under more or less tension which is utilized to normally maintain the valves 17 and 18 in their respective positions shown in Figure 2, in which positions the exit openings 10 and 12 leading from the passages 7 and 11, respectively, are closed. In order to limit the movement of the valves 17 and 18 in one direction the shafts 27 and 28 are provided with fingers 46 and 47 adapted to engage the stem 6, as shown most clearly in Figure 3.

To the under side of the casting 5 there is connected a pair of lugs 48 within which is journaled a transversely disposed shaft 49 upon which is mounted a movable actuating plate 50 having ears 51 formed integral therewith through which the transversely disposed shaft 49 extends. One of these ears, as shown in Figure 7, is provided with a stop 52 which is adapted to engage the casting 5 to limit the movement in one direction of the rocker member 50, as will hereinafter more clearly appear. This same ear is provided with a cam face 53 adapted to engage and cooperate with the arm 41 to move the same and thereby effect an opening of the valve 17. To the rocker member 50 there is pivotally connected a latch lever 54, the pivotal connection between the latch lever and rocker member being indicated by the numeral 55. This latch lever is provided at its opposite end with a depending roller 56 adapted to ride over the slightly curved face

of a lift finger 57 carried by the rocker member 50. The latch lever is provided with a depending trip arm 58 carrying at its lower end a trip finger 59 disposed at right angles thereto. At that end of the latch lever 54 to which the roller 56 is connected there is carried an upstanding pin or lug 60 adapted to engage and cooperate with the arm 40 to effect such movement of the shaft 28 as will cause the valve 18 to be opened against the influence of the spring 45 in a manner hereinafter more particularly described. The latch lever 54 is maintained normally in its position shown in Figures 3 and 5 through the instrumentality of a spring 61 coiled about the pivot 55 and having one end maintained within a notch 62 formed in the ear 51, the other end of this spring being suitably connected to the latch lever 54 as shown at 63. By arranging the spring 61 as described and connecting the same to the flange 51 and the latch lever 54 it will be appreciated that this single tension means may be utilized to maintain the latch lever 54 and the oscillating member 50 in their respective positions most clearly understood from an inspection of Figures 3 to 7, inclusive. It will be noted that when these elements are normally positioned the free end of the latch lever 54 is located directly over the finger 57 which position is necessary in order to permit simultaneous opening of the valves 17 and 18 when it is desired to dispense the liquid simultaneously from the passages 7 and 11.

To the hub member 38 there is connected a handle 64 which is adapted to be operated manually when it is desired to rotate the shaft 28 and open the valve 18 independently of the valve 17, thereby permitting the liquid to escape from the passage 11 only, which passage as hereinbefore explained is adapted to communicate with a source of milk supply.

The entire structure herein shown and described is adapted to be suitably supported upon a base or other supporting structure, not shown, and is also adapted to be provided with a housing or cover, not shown, enclosing the several operative elements of the apparatus to prevent the same against injury and protect them from dirt or other undesirable foreign matter which might otherwise collect thereon.

The apparatus embodying my invention although not restricted to such use is particularly adapted to be used in restaurants and operated by a counterman for dispensing either milk, coffee or a mixture of the two liquids. When it is desired to dispense only coffee, a cup or other suitable container is introduced intermediate the arcuate shaped arms 65 carried by the depending lever 66 connected to the rocker member 50 and at the same time brought into engage-

ment with the trip finger 59. Upon further introduction of the cup or other receptacle the trip arm 58 is moved in the direction of the arrow A shown in Figure 1 whereupon the latch lever 54 is moved about its pivot 55 against the influence of the spring 61 causing the free end of the latch member to disengage from the finger 57 and so position itself with respect thereto as to permit the finger 57 to move in an unobstructed manner. After the free end of the latch lever 54 has been moved a sufficient distance to permit the finger 57 to clear the same the cup or other receptacle is further introduced causing the lever 66 to move in the direction of the arrow B shown in Figure 1. This movement of the lever 66 causes the rocker member 50 to move about the axis of the shaft 49 as a pivot whereupon the cam face 53 of the flange 51 lifts the arm 41 thereby rotating the shaft 27 and effecting a lifting or opening of the valve 17 to permit the egress of liquid from the passage 7 through the exit opening 10. The valve 18 under such conditions is permitted to remain closed for the reason that the free end of the latch lever 54 having been moved as above described from its position directly over the finger 57 permits this finger to move in an unobstructed manner.

In the event it is desired to dispense only milk, for example, from the passage 11 a lever 64 connected to the hub member 38 is depressed against the tension of the spring 45 whereupon the shaft 28 is rotated and the valve 18 is lifted thereby opening the exit opening 12. It will be appreciated that after a quantity of coffee has been dispensed the lever 64 may be depressed to release a desired quantity of milk so that the resultant content of the cup or receptacle previously introduced may be that of a desired quantity of coffee into which has been introduced a desired proportion of milk, such proportions of course being governed or determined by the length of time each of these liquids has been dispensed independently of each other.

Should it be desired to operate the two valves 17 and 18 simultaneously in order to dispense equal amounts of liquid from their respective sources of supply, the cup or other receptacle is introduced between the arcuate shaped arms 65 without disturbing the position of the depending trip arm 58 and the lever 66, upon further introduction of the cup, is moved a sufficient distance in the direction of the arrow B shown in Figure 1 to appreciably move the rocker member 50 about the shaft 49 as an axis. With the latch lever 54 positioned as shown most clearly in Figures 3 to 5, inclusive, the free end of the same is lifted as the rocker member 50 is moved and by reason of the en-

gagement between the free end of the latch lever 54 and the arm 40 the shaft 28 is rotated thus effecting operation of the valve 18 and opening of the exit opening 12. At the same time the valve 18 is opened the valve 17 is simultaneously opened in the manner hereinbefore described. Upon withdrawing the cup or other receptacle from engagement with the lever 66 the valves 17 and 18 are moved to their normal positions, shown in Figure 2, through the instrumentality of the springs 44 and 45 and the lever 66 is moved to its normal position shown most clearly in Figure 1.

While I have shown and described what I at present consider the preferred form of my invention it is to be understood that various changes in the size, shape, arrangement and proportion of elements may be resorted to without departing from the spirit of the invention or the scope of the subjoined claims.

I claim:

1. A liquid dispensing apparatus adapted to be connected to different sources of liquid supply comprising a body portion, valves associated with said body portion and adapted to control the egress of liquid from said sources of supply, means for actuating said valves simultaneously, and means associated with said valve-actuating means for rendering one of said valves inoperative.

2. A liquid dispensing apparatus adapted to be connected to different sources of liquid supply comprising a body portion, valves associated with said body portion and adapted to control the egress of liquid from said sources of supply, and a common means adapted to be so actuated as to either open one of said valves independently of the other or both of said valves simultaneously.

3. A liquid dispensing apparatus adapted to be connected to different sources of liquid supply comprising a body portion, valves associated with said body portion and adapted to control the egress of liquid from said sources of supply, means for actuating said valves simultaneously, means associated with said valve-actuating means for rendering one of said valves inoperative, and auxiliary means for actuating one of said valves independently of the first mentioned valve-actuating means.

4. A liquid dispensing apparatus adapted to be connected to different sources of liquid supply comprising a body portion having liquid carrying passages formed therein and adapted to communicate with said sources of supply, valves associated with said body portion and adapted to control the egress of liquid from said passages, said valves being pivotally connected to said body portion, an actuating lever adapted to be moved with respect to said body portion, means so connecting said lever with said valves as to

effect simultaneous operation of said valves upon movement of said lever, and means for severing operable connection between said lever and one of said valves.

5. A liquid dispensing apparatus adapted to be connected to different sources of liquid supply comprising a body portion having liquid carrying passages formed therein and adapted to communicate with said sources of supply, valves associated with said body portion and adapted to control the egress of liquid from said passages, said valves being pivotally connected to said body portion, an actuating lever adapted to be moved with respect to said body portion, means so connecting said lever with said valves as to effect simultaneous operation of said valves upon movement of said lever, and means for severing operable connection between said lever and one of said valves, said severing means being in the form of a latch cooperatively associated with said lever and adapted to be influenced in its operation by the movement of said lever to actuate one of said valves simultaneous with the operation of the other of said valves.

6. A liquid dispensing apparatus adapted to be connected to different sources of liquid supply comprising a body portion having liquid carrying passages formed therein and adapted to communicate with said sources of supply, valves adapted to open and close said passages, means for actuating said valves simultaneously, said valve-actuating means being in the form of a lever, a rocker member adapted to be moved by said lever, means operatively connecting said rocker member with said valves for effecting simultaneous operation thereof, and means for severing the operative connection between said valve-actuating means and one of said valves whereby one of said valves is rendered inoperative during the operation of the other of said valves.

45. 7. A liquid dispensing apparatus adapted to be connected to different sources of liquid supply comprising a body portion having liquid carrying passages formed therein and adapted to communicate with said sources of supply, valves adapted to open and close said passages, means for actuating said valves simultaneously, said valve-actuating means being in the form of a lever, a rocker member adapted to be moved by said lever, means operatively connecting said rocker member with said valves for effecting simultaneous operation thereof, and means for severing the operative connection between said valve-actuating means and one of said valves whereby one of said valves is rendered inoperative during the operation of the other of said valves, said means for severing operative connection between one of said valves and said rocker member being in the form of a movable latch lever pivotally

connected to said rocker member and adapted to be moved with respect thereto.

8. A liquid dispensing apparatus adapted to be connected to different sources of liquid supply comprising a body portion having liquid carrying passages formed therein and adapted to be connected to said sources of supply, valves adapted to open and close said passages, means for actuating said valves simultaneously, said valve-actuating means being in the form of a lever, a rocker member adapted to be moved by said lever, means operatively connecting said rocker member with said valves for effecting simultaneous operation thereof, means for severing the operative connection between said valve-actuating means and one of said valves whereby one of said valves is rendered inoperative during the operation of the other of said valves, said means for severing operative connection between one of said valves and said rocker member being in the form of a movable latch lever pivotally connected to said rocker member and adapted to be moved with respect thereto, and means tending to normally retain said latch lever so positioned that the simultaneous operation of said valves is effected upon the movement of said lever.

9. A liquid dispensing apparatus adapted to be connected to different sources of liquid supply comprising a body portion having liquid carrying passages formed therein and adapted to communicate with said sources of supply, valves adapted to open and close said passages, means for actuating said valves simultaneously, said valve-actuating means being in the form of a lever, a rocker member adapted to be moved by said lever, means operatively connecting said rocker member with said valves for effecting simultaneous operation thereof, means for severing the operative connection between said valve-actuating means and one of said valves whereby one of said valves is rendered inoperative during the operation of the other of said valves, said means for severing operative connection between one of said valves and said rocker member being in the form of a movable latch lever pivotally connected to said rocker member and adapted to be moved with respect thereto, means tending to normally retain said latch lever so positioned that the simultaneous operation of said valves is effected upon the movement of said lever, and auxiliary valve-actuating means adapted to operate one of said valves independently of the other.

10. A liquid dispensing apparatus adapted to be connected to different sources of liquid supply comprising a body portion having liquid carrying passages formed therein and adapted to communicate with said sources of supply, valves adapted to open and close said passages, means for ac-

tuating said valves simultaneously, said valve-actuating means being in the form of a lever, a rocker member adapted to be moved by said lever, means operatively connecting said rocker member with said valves for effecting simultaneous operation thereof, means for severing the operative connection between said valve-actuating means and one of said valves whereby one of said valves is rendered inoperative during the operation of the other of said valves, said means for severing operative connection between one of said valves and said rocker member being in the form of a movable latch lever piv-

otally connected to said rocker member and adapted to be moved with respect thereto, means tending to normally retain said latch lever so positioned that the simultaneous operation of said valves is effected upon the movement of said lever, auxiliary valve actuating means adapted to operate one of said valves independently of the other, and yieldable means associated with said valves for retaining the same in intimate engagement with said body portion. 15
